UNITED STATES PATENT OFFICE

111,236

DESIGN FOR A BOOK END

Edwin Beer, Athens, Ga.

Application June 7, 1938, Serial No. 77,642

Term of patent 3½ years

To all whom it may concern:

Be it known that I, Edwin Beer, a citizen of the United States, residing in Athens, Georgia, in the county of Clarke and State of Georgia, have invented a new, original, and ornamental Design for Book Ends, of which the following is a specification, reference being had to the accompanying drawing, forming part thereof.

In the drawing:

Fig. 1 is a perspective view of a book end

made according to my new design and illustrating the rear and right side of the book end;

Fig. 2 is a front elevation of the book end;

Fig. 3 is a back elevation of the book end; and

Fig. 4 is a side elevation thereof, the right and left sides being identical in appearance.

I claim:

The ornamental design for a book end, substantially as shown and described.

EDWIN BEER.
